CLAIM

We claim the ornamental design for the overlay for electronic device, substantially as shown and described.

DESCRIPTION

FIG. 1 is a top perspective view of an overlay for electronic device, according to a first embodiment;

FIG. 2 is a bottom perspective view of the overlay for electronic device, according to the first embodiment;

FIG. 3 is a top plan view of the overlay for electronic device, according to the first embodiment;

FIG. 4 is a side elevational view of the overlay for electronic device, according to the first embodiment, where the opposite side elevational view is a mirror image thereof;

FIG. 5 is a bottom plan view of the overlay for electronic device, according to the first embodiment;

FIG. 6 is a top plan view of the overlay for electronic device in a folded configuration, according to the first embodiment;

FIG. 7 is a top perspective view of an overlay for electronic device, according to a second embodiment;

FIG. 8 is a bottom perspective view of the overlay for electronic device, according to the second embodiment;

FIG. 9 is a top plan view of the overlay for electronic device, according to the second embodiment;

FIG. 10 is a side elevational view of the overlay for electronic device, according to the second embodiment, where the opposite side elevational view is a mirror image thereof;

FIG. 11 is a bottom plan view of the overlay for electronic device, according to the second embodiment; and,

FIG. 12 is a top plan view of the overlay for electronic device in a folded configuration, according to the second embodiment.
